UNITED STATES PATENT OFFICE.

ALFRED B. LEMON, OF PROVIDENCE, RHODE ISLAND.

BADGE.

Application filed February 15, 1922. Serial No. 536,645.

To all whom it may concern:

Be it known that I, ALFRED B. LEMON, a citizen of the United States, residing at Providence, in the county of Providence and State of Rhode Island, have invented 5 certain new and useful Improvements in Badges, of which the following is a specification.

This invention relates to improvements 10 in the construction of an emblem, badge, charm or the like, and has for its object to provide such a badge or charm adapted to be attached to and used as a pendent on watch chains or neck chains or to be 15 attached to rings, cuff buttons or other articles of jewelry to be used as an emblem or badge or charm, the device having an outline of the desired significance and having an opening through it preferably in the 20 form of a symbolic arch and a wing or closure member being mounted on either one or both faces of the body portion of the emblem to be swung outwardly or moved to expose this opening, when desired.

25 With these and other objects in view the invention consists of certain novel features of construction, as will be more fully described, and particularly pointed out in the appended claims.

30 In the accompanying drawings:

Figure 1 is a front view of the device showing the gate or closure member in closed position covering the opening through the body portion.

35 Figure 2 is the same as Figure 1 and showing one of the gate members as swung to open position exposing the arch permitting the symbol on the inner face of the opposite gate member to also be observed 40 as though in the distance.

Figure 3 is a central sectional edge elevation showing the opening through the middle of the emblem-body and showing the closure gate members as hinged on opposite sides of the body portion and both in open or raised position.

45 In my improved construction of badge or emblem I have provided a central opening 12 through the body portion thereof, 50 which opening is preferably in the form of a symbolic arch, but the opening may be made in any other desired shape, and on opposite sides of this body portion I have hung gates or closure members 10 and 11 on 55 their respective hinges 13 and 14 to be

swung into position to cover both entrances to the opening or they may be raised to expose the same:

These wings or closure members are each 60 adapted to carry symbols 15 and 17 respectively, on their outer faces and 16 and 18 on their respective inner faces if desired, whereby when the gate 10 is raised into the position illustrated in Figure 2 the gate 11 being closed, the opening in the 65 body is exposed and the symbol 16 on the inner face of gate 11 may be observed through the arch, the lifting of this gate also exposes the second flight of steps 19 leading to the arch thus producing the effect of the gateway of an ancient temple 70 and on the wall at the farther end of which is observed a significant symbol 16, thus producing a very novel and attractive effect in an emblem of this character. 75

In order that a variety of effects may be produced the significance of symbol 18 may be different from symbol 16 and so when gate 10 is closed and gate 11 is open the symbol on the inner face of this gate may 80 be observed through the arch upon the distant wall of the temple in place of the one exposed when looking through from the opposite direction.

The emblem is very handsome and attractive in appearance and by providing an opening therethrough in combination with the swinging gates on the opposite sides thereof new and novel effects are produced all of which may be symbolic of the 85 order to which the emblem applies.

I have shown and described the closure members or gates as being hinged above the opening but these gates may be arranged in any desired form and hung in 90 any desired way to be moved into position to expose the arch or opening. I have also shown a gate as mounted on both sides of the body of the emblem, but a gate may be 95 hung on but one side of the body if desired, to be moved to either expose or close the opening.

The foregoing description is directed 100 solely towards the construction illustrated, but I desire it to be understood that I reserve the privilege of resorting to all the 105 mechanical changes to which the device is susceptible, the invention being defined and limited only by the terms of the appended 110 claims.

I claim:

1. A badge comprising a body having an outline of the desired significance and having an unobstructed opening through it shaped to carry a significance different from that of the body, and a hinged closure plate mounted on opposite sides of said body adapted to be moved independently to expose said opening and permit an unobstructed view of the opening from either side of the body.

10 2. A badge comprising a body having an outline of a certain significance and pro-

vided with an unobstructed opening through it, and a closure member for said opening 15 mounted on each of the opposite sides of said body, each carrying a symbol on its inner face and each of said members being adapted to be moved independently of the other to expose said opening through which 20 the symbol on the opposite member may be observed.

In testimony whereof I affix my signature.

ALFRED B. LEMON.
